US00D518008S

(12) **United States Design Patent** (10) **Patent No.:** **US D518,008 S**
Peng (45) **Date of Patent:** **** Mar. 28, 2006**

(54) **CARRIAGEABLE MULTIMEDIA DISPLAY DEVICE**

(75) Inventor: **Juen Tien Peng**, Chung Li (TW)

(73) Assignee: **Action Electronics Co., Ltd.**, Chung Li (TW)

(**) Term: **14 Years**

(21) Appl. No.: **29/220,144**

(22) Filed: **Dec. 28, 2004**

(51) **LOC (8) Cl.** **14-03**

(52) **U.S. Cl.** **D14/129**

(58) **Field of Classification Search** **D14/125-134, D14/239, 371, 136, 374-376; 312/7.2; 348/836, 348/838, 180, 184, 325, 739; 341/12; 248/917-924, 248/291.1, 465; 345/104, 133, 156, 168, 345/87, 173; 720/605, 669, 600, 655; 369/99, 369/197; 455/344-347**

See application file for complete search history.
